UNITED STATES PATENT OFFICE

164,888

COMBINED SLIPPER AND SOX

Alex Lee Wallau, New York, N. Y.

Application August 15, 1951, Serial No. 16,284

Term of patent 3½ years

(Cl. D47—7)

To all whom it may concern:

Be it known that I, Alex Lee Wallau, a citizen of the United States of America, residing in New York, county of New York, and State of New York, have invented a new, original, and ornamental Design for a Combined Slipper and Sox, of which the following is a specification, reference being had to the accompanying drawing, forming part thereof.

The figure on the drawing is a perspective view of a combined slipper and sox showing my new design.

The opposite side of the combined slipper and sox is substantially the same in appearance as that shown.

I claim:

The ornamental design for a combined slipper and sox, substantially as shown and described.

ALEX LEE WALLAU.
